UNITED STATES PATENT OFFICE.

ROSS B. JOHNSON, OF CHEROKEE, IOWA.

RAIL-OILING MACHINE.

1,307,498.

Specification of Letters Patent. Patented June 24, 1919.

Application filed June 22, 1918. Serial No. 241,401.

To all whom it may concern:

Be it known that I, Ross B. JOHNSON, a citizen of the United States, residing at Cherokee, in the county of Cherokee and State of Iowa, have invented certain new and useful Improvements in Rail-Oiling Machines, of which the following is a specification, reference being had to the accompanying drawings.

10 This invention relates to machines for spraying liquid, and particularly to machines for applying oil to the bolts and angle bars of railroad rails.

The general object of the invention is to 15 provide a machine of the character stated designed to travel upon a railroad track and to be driven by any suitable power, the truck of the machine carrying an oil tank and valve controlled spraying nozzles so arranged 20 as to spray oil upon the joints, bolts, and fish plates of railroad tracks.

At the present time, rail joints have to be oiled by hand and the oil or other like material is put on with a brush. One man can 25 average one mile of track a day using about five or six gallons of oil to the mile, and another object of the device is to provide an oiling machine of the character stated whereby the amount of oil may be reduced 30 and the amount of track oiled increased.

A further object is to provide a construction of this character in which oil is forced from the tank under pressure by means of an air pump connected to the tank and 35 driven preferably from the axle of the truck upon which the tank is mounted.

A further object is to provide simple means whereby the oiling pipes may be raised or lowered and whereby the flow of 40 oil through the pipes may be readily controlled.

Other objects will appear in the course of the following description.

My invention is illustrated in the accompanying drawings, wherein:—

Figure 1 is a side elevation of my improved track oiler;

Fig. 2 is a front elevation thereof; and

Fig. 3 is a detailed sectional view showing 50 the manner of connecting the piston rod to the crank 24.

Referring to the drawings, 10 designates a truck of any suitable construction, and which may be driven or caused to travel 55 over the rails in any suitable manner, this truck being supported upon wheels 11 and

upon axles 12 resting on the rails 13. Mounted upon the truck, in any suitable manner, is the oil tank 14. This will preferably contain about one hundred gallons 60 of oil and is provided with the pressure gage 16 and with the check valve 17 having a nipple. A pump cylinder 18 is operatively supported upon the frame of the car and from this pump cylinder extends a flexible pipe 19 to the nipple 17. Thus air may be pumped into the tank 14. The pump may be of any suitable construction and is provided with a piston 20 reciprocated by any suitable means connected to the axle 12. 70

Preferably the piston carries at its outer end a head 21 through which passes the screw-threaded wrist pin 22, the head being held in place upon the wrist pin by nuts 23, this wrist pin passing through a thin metal 75 crank arm 24 mounted upon one of the axles 12. Any other suitable construction for this purpose may be used, however. One end of the cylinder is hingedly connected to the frame of the truck so that the cylinder may 80 oscillate as the piston reciprocates.

Extending from the tank 14 is a discharge pipe 25 having therein the valve 26 whereby passage through the discharge pipe may be controlled, and this discharge pipe extends 85 forward to the forward end of the truck and is there connected to laterally extending branches 27 having turn cocks 28, whereby passage through the branches may be quickly controlled. Swingly connected 90 to the ends of the pipes 27 are the downwardly and forwardly extending pipes 29, each terminating at its lower end in a T 30 from which extends lateral branch pipes 31 which are then formed to extend downward 95 and forward and then inward and are connected to valve nozzles 32 whereby discharge from the nozzles may be controlled.

For the purpose of raising or lowering the downwardly and forwardly extending 100 pipes 29, I provide a lever 33 operating over a rack 34 and operatively connected to the pipes 29 by means of the rods 35. By shifting the lever, the oil pipes may be raised or lowered. These levers permit the spray 105 nozzles to be raised or lowered when going over crossings and through switches and does away with the necessity of stopping to raise the pipes. The valves 28 are quick-acting valves, so as to shut off or turn on 110 the supply of oil very quickly and the pet cocks 32 are designed particularly to con-

trol the flow of oil from the nozzles. The inner end of the piston is preferably adjustably engaged with the crank so that by setting the piston ahead, that is, toward the 5 axis of the wheel, the stroke of the piston will be shortened and by setting it toward the rim of wheel, the stroke will be lengthened, thus to regulate the amount of air which is pumped into the tank and to cause 10 the air to replace the oil which is ejected from the spray pipe.

In the practical use of this invention the tank is filled, but if there should be no pressure within the tank, then the car is run 15 backward on the rails for a short distance until about 30 pounds of pressure is secured within the tank. Then the tank is run ahead without using oil to the same distance and thus the pressure is increased to 60 pounds. 20 Then the valves 26, 28 and 32 are opened and the car is forced ahead. By watching the air gage, the operator can set the pump to keep up the same pressure at all times. A small pressure relief valve is mounted in the 25 top of the tank which will hold the pressure at a certain point but relieve it if the pressure is too great. The tank is designed to be pushed by a motor car and run about five miles per hour. There will be a man on 30 each side of the truck to turn on the oil through the valves 28 as the sprayer pipes come to a joint. This device will oil every bit of angle bar and bolts and, furthermore, it sprays oil into the space between the angle 35 bars and the rails and at the ends where ordinarily no oil is applied. This oiling device will oil about five miles of track an hour, using about four gallons of oil per mile.

40 While I have illustrated a particular embodiment of my invention, yet it will be obvious that it may be changed in many ways, without departing from the spirit of the invention, as defined in the appended claims.

45 Having described my invention, what I claim is:—

1. A fish plate oiler comprising a wheeled truck, a tank mounted thereon, track oiling 50 pipes mounted upon the truck for vertical movement and having branches at their lower ends spaced from each other a distance greater than the head of a rail and adapted to straddle a rail and having spray nozzles discharging toward the rail straddled by the branches, said branches and noz-

zles when the oiling pipes are lowered being disposed below the level of the truck wheels, means for compressing air within the tank, and manually controllable means 60 for raising and lowering the track oiling pipes.

2. A fish plate oiler comprising a truck, a tank mounted thereon, track oiling pipes mounted upon the truck and having 65 branches at their lower ends straddling a rail and having spray nozzles discharging toward the rail straddled by the branches, and means for compressing air within the tank, the spray nozzles being provided with 70 valves for controlling the size of the spray discharged and the oil pipes being provided with valves controlling the volume of oil discharged from the tank.

3. Means for oiling track comprising a 75 truck having wheels adapted to run upon the track, a tank supported upon the truck, a power operated air compressing pump connected to the tank, laterally extending pipes operatively connected to the tank and having 80 quick-operating valves, discharge pipes extending downward from said laterally extending pipes and disposed over the rails and having branches straddling the rails, and carrying valve controlled nozzles discharging toward the rails, and means for 85 raising or lowering the discharge pipes.

4. Means for oiling rails comprising a truck having wheels engaging the rails, a tank mounted thereon, an air pump operatively connected to be driven by the wheels and operatively connected to the pump, a discharge pipe leading from the tank and having a valve, laterally disposed pipes having manually operable quick-acting valves 95 and extending to points above the rails, downwardly extending pipes mounted in advance of the truck and connected to said laterally extending pipes and oscillatable in a vertical plane, each of said downwardly and 100 forwardly extending pipes having lateral branches at the ends embracing the rail and having inwardly extending valved discharge nozzles, and levers operatively connected to the forwardly extending pipes whereby they 105 may be raised or lowered.

In testimony whereof I hereunto affix my signature in the presence of two witnesses.
ROSS B. JOHNSON.
